UNITED STATES PATENT OFFICE.

WINTHROP L. JACOBS, OF JERSEY CITY, NEW JERSEY, ASSIGNOR TO HARTFORD CARPET COMPANY, OF HARTFORD, CONNECTICUT.

DESIGN FOR CARPET.

SPECIFICATION forming part of Design No. 11,875, dated July 20, 1880.

Application filed February 12, 1880. Term of patent 3½ years.

To all whom it may concern:

Be it known that I, WINTHROP L. JACOBS, of Jersey City, county of Hudson, and State of New Jersey, have invented a new and original 5 Design for Carpets, of which the following is a specification.

This invention relates to a new and original design for carpets, oil-cloths, and similar fabrics.

10 It consists in the novel grouping and configuration of figures, hereinafter more fully described.

The accompanying photograph illustrates a face view of a carpet having my new design.

15 On the background of the carpet is a group, A, composed of a central star-shaped figure surrounded by smaller radiating stars, forming a diamond.

20 B is a group composed of a central Maltese-cross-shaped figure, from the top of which projects a vase, a, and from one of the arms an obliquely-placed vase-like figure, a'. From the under side of the cross a bar extends, on which are figures b d e f t.

25 C is a group composed of a central star, g, and radiating arms terminating with triangular figures h. Group C is connected by bars with figures G H, group B, and intermediate figures.

30 D is a crown-shaped figure placed edgewise and connected with A by a bar.

E is an obliquely-placed figure, composed of a number of irregularly-shaped small figures.

35 F is a T-shaped figure obliquely placed, and having at the junction of the head and stem star-shaped figures i i'.

G is an inverted leaf-like figure, and H is an inverted vase-like figure with pendants, both of said figures being suspended from a 40 bar that connects figures E F.

I is a cross-shaped figure resting on a crown, j, and surmounted by a small cross, l, and the arms are ornamented with small figures and stems.

45 K is a group composed of a rosette, m, surrounded by small ornamental figures and with a projecting stem terminating with a figure, m'. Said group is connected by a bar with the group C.

50 L is a fan-shaped figure inserted between two oblique bars.

M is a vase-like figure placed on a bar which connects with the group K and with the figure N, which is a fan-shaped figure. From the bar which connects figures M N project several 55 figures composed of triangles.

O is a figure resembling a basket with flowers, which is placed in a horizontal position on the bar connecting group C and figure L.

P is a group composed of a large star-shaped 60 figure, p, a smaller figure, o, and a group of triangles, q.

Q is a group composed of figures resembling pyramids, which are placed in a horizontal position, so as to form two oppositely-turned 65 figures on one stem.

R is a vase-like figure placed on a bar that joins the figures N S, said figure S being a collection of triangles placed in a row.

On the bars which connect the various groups 70 and figures are numerous small ornamental figures n.

I claim—

1. The design for a carpet, consisting of the group B, composed of central Maltese-cross-shaped figure and of figures a, a', b, d, e, f, and t, substantially as shown. 75

2. The design for a carpet, consisting of the group C, composed of figures g h, substantially as shown. 80

3. The design for a carpet, consisting of the figure I, crown j, and cross l, substantially as shown.

4. The design for a carpet, consisting of the group K and figure m', substantially as shown. 85

5. The design for a carpet, consisting of the figure M, substantially as shown.

6. The design for a carpet, consisting of the figure O, substantially as shown.

7. The design for a carpet, consisting of the group P, substantially as shown. 90

8. The design for a carpet, consisting of the figure Q, substantially as shown.

9. The design for a carpet, consisting of the group A and figure D, substantially as shown. 95

10. The design for a carpet, consisting of the groups B C E F G H, containing figures b d e f t a a' g h and connecting-bar, substantially as described.

11. The design for a carpet, consisting of 100 the groups K C, figures M N, and connecting-bars, substantially as shown.

12. The design for a carpet, consisting of the groups C K, figures L O, and connecting-bars, substantially as described.

13. The design for a carpet, consisting of 5 the figures R N M s and connecting-bars, substantially as shown.

14. The design for a carpet, consisting of the groups A B C K P, figures D E F G H I

L M N O Q R S, connecting-bars and ornaments, and the background of the carpet, substantially as shown. 10

WINTHROP L. JACOBS.
